[57] CLAIM

The ornamental design for a display device for use with colored flicker plates, as shown and described.

DESCRIPTION

FIG. 1 is a front elevation view of a display device for use with colored flicker plates, showing my new design;
FIG. 2 is a bottom view thereof;
FIG. 3 is a right side elevation view, the left side being a mirror image thereof;

FIG. 4 is a somewhat enlarged sectional view taken along line IV—IV of FIG. 1; and

FIG. 5 is a front perspective view thereof, with the flicker plates shown in broken lines for illustrative purposes only.

The rear of the device is substantially planar and unornamented.
